UNITED STATES PATENT OFFICE.

SIMON B. DEXTER, OF GLENDALE, MONTANA.

ASH-PAN.

SPECIFICATION forming part of Letters Patent No. 450,005, dated April 7, 1891.

Application filed August 20, 1890. Serial No. 362,511. (No model.)

To all whom it may concern:

Be it known that I, SIMON B. DEXTER, of Glendale, in the county of Beaver Head and State of Montana, have invented a new and 5 Improved Ash-Pan, of which the following is a specification, reference being had to the annexed drawings, forming a part thereof, in which—

Figure 1 is a side sectional elevation of my 10 improved ash-pan. Fig. 2 is a plan view of the grate and ash-pan, taken on line 2 2 in Fig. 1; and Fig. 3 is a vertical transverse section, taken on line 3 3 in Fig. 2.

Similar letters of reference indicate corresponding parts in all the views.

The object of my invention is to provide an 15 ash-pan applicable to furnaces of various kinds, but more especially designed to be used in my improved ore-roasting furnace, described in application, Serial No. 287,374, filed October 6, 1888.

My invention consists in an ash-pan provided with a water-discharge pipe, and arranged in connection with the water-grate so 20 as to receive the cooling-water discharged by the grate and convey it, together with the ashes, to the discharge-pipe leading from the furnace.

In the furnace-wall A is formed a fire-chamber B, in which is supported the tubular grate C. The said tubular grate C receives the 25 cooling-water through the pipe a and discharges it from the nozzle b. In the chamber B, below the grate C, is arranged the ash-

pan D, furnished with a discharge-pipe c, 35 which is of sufficient size to convey away the water discharged into the pan by the nozzle b, together with the ashes deposited by the fire on the tubular grate C.

The water conveyed to the grate by the pipe 40 a is preferably taken from the pipes and passages of the cooling apparatus of other parts of the furnace; but I do not confine myself to this arrangement. The ashes and cinders falling through the grate into the ash-pan D 45 are carried away with the water through the discharge-pipe c, thereby obviating the necessity of handling the ashes.

Having thus described my invention, I claim as new and desire to secure by Letters Patent—

1. The combination, with the tubular grate C, of the ash-pan D, furnished with the discharge-pipe c, and adapted to receive water from the tubular grate, substantially as specified. 55

2. The combination of the tubular grate C, furnished with the water-supply pipe a, and the discharge-nozzle b, and the ash-pan D, furnished with the discharge-pipe c, and 60 adapted to receive the ashes and cinders falling through the tubular grate C, and the water-discharge from the tubular grate, substantially as specified.

SIMON B. DEXTER.
